CLAIM

The ornamental design for an internal electronics housing, as shown and described.

DESCRIPTION

FIG. 1 is a perspective view of the internal electronics housing;

FIG. 2 is a top view of the internal electronics housing of FIG. 1;

FIG. 3 is a bottom view of the internal electronics housing of FIG. 1;

FIG. 4 is a right side view of the internal electronics housing of FIG. 1;

FIG. 5 is a left side view of the internal electronics housing of FIG. 1;

FIG. 6 is a front view of the internal electronics housing of FIG. 1;

FIG. 7 is a rear side view of the internal electronics housing of FIG. 1;

FIG. 8 is a front view of the internal electronics housing of FIG. 1 in an container; and,

FIG. 9 is an enlarged view of the front view of the internal electronics housing taken from FIG. 8.

In the accompanying drawings, the evenly-spaced broken lines in the figures depict portions of the internal electronics housing that form no part of the claimed design and/or depict the nature and environmental use of the claimed design. The dot-dot-dash broken lines encircling portions of the claimed design that are illustrated in the enlargement form no part of the claimed design.

(Continued)

The drawings include a symbolic break in length of the article represented by wavy break lines. The appearance of any portion of the article between the break lines forms no part if the claimed design.
